LOOSE LEAF BINDER

Charles B. Hammen, East Orange, N. J., assignor
to National Blank Book Company, Holyoke,
Mass., a corporation of Massachusetts

Application August 1, 1936, Serial No. 93,750

1. Claim. (Cl. 129—7)

This invention relates

This invention relates to improved loose leaf binder constructions and particularly to improvements in making such constructions for use in both punching and binding loose leaf sheets.

5 According to the principal object of the present invention, I make an ordinary book binding case consisting of back panel with covers hinged at the sides; to such a back panel I attach the metal or mechanism of the loose leaf structure such as
10 the toggle mechanism, spring plate, and holding rings or prongs common in loose leaf books and I incorporate a sheet punching device in such mechanism attached to and hidden by the back panel without substantially changing the usual
15 appearance of the book. That is to say, the sheet punching mechanism is incorporated in the metal parts of a perfectly simple ring book construction and without any substantial change in the appearance of the book.

20 One way of accomplishing this object is to proceed as follows. The binder case is made up as usual. It is a common practice to put a metal stiffening plate in the back panel construction of the case and I fasten such a plate on the inside 25 face of the back panel in the binder case of my construction. It is common practice to attach the parts of the ring metal mechanism to the back panel. But I mount such ring mechanism on top of a metal plate that is provided for co-operation with the stiffening plate of the back panel so that the two metal plates can work together with tools provided thereon, as a punching means for the loose leaf sheets. They work 30 in the fashion of a little platen punch press, on the back panel. The bed-plate preferably carries the female part of the punching die and the movable plate carries the male part on the under side and the ring mechanism on the top side. 35 Now, if, as an illustration, the two plates are 40 hinged together at the sides with a latch at one end, the improved structure in one of its specific forms is complete. This complete structure is perfectly simple in appearance as it appears as the simplest form of ring book.

45 The user who would ordinarily object to having a simple ring book cluttered up with a sheet perforating mechanism will accept the new book structure as he would a simple ring book. He will not see or be conscious of the punch press
50 unless he wants to use it. At all other times the structure is made as if no more were in it than is in the customary simple form of book. It is common practice for some users to stab the paper holes by the ends of the rings or prongs as a
55 means to locate holes in sheets not otherwise per-

forated at the binding margin. New sheets are commonly put in a loose leaf book that way, but it is a sloppy expedient and tends to create a prejudice against loose leaf books. The temporary advantage of the expedient is forgotten but the sloppy appearance of a book having poorly applied sheets is ever before the user. With the present invention this difficulty in loose leaf book use can be avoided with sufficient convenience to persuade against the former sloppy practice. And, furthermore, the improved binder may be made up with definite advantages to the manufacturer.

The accompanying drawing discloses the invention.

Fig. 1 is a perspective view of a binder case; Fig. 2 is a perspective view of a stiffening plate for the back panel and formed to serve also as a bed-plate for the perforating mechanism.

Fig. 3 is a perspective view of a movable plate 20 as part of the punch press and formed to serve also as means of attaching the loose leaf mechanism:

Fig. 4 is a perspective view of the completed loose leaf binder with the punch press attached on the back panel and supporting the loose leaf mechanism. 25

Fig. 5 is a partial end view of Fig. 4 with the parts of the punch plates separated.

Referring to the drawing:

The binder case of Fig. 1 with back panel 2 and hinged covers 3 and 4 may be made up in the customary way, by usual automatic machinery. There need be no difference in the binder case as compared to the usual loose leaf book. 35

The plate 5 of Fig. 2 may be fastened by rivets through holes 5' to cover the inside face of the back panel. In this position it will stiffen the back panel and thus function as part of the back panel. As shown in its detailed form, plate 5 will also function as the bed-plate of a little platen punch press. It has die holes 6, square edge 7 to locate the paper, hinge parts 8 at the sides, a wide shallow recess 6' on the under side opening out at the end and surrounding each hole 6 and latch notch 9.

The plate 10 of Fig. 3 is formed to function as the movable plate of the punch press. It has male parts 11 for the punch press, to match holes 6, a cut-out recess 17 to match the square edge device 7 of the other plate, hinge parts 12 for attachment to hinge parts 8 of plate 5 and spring latch 9.

In Fig. 4 there is shown the usual loose leaf **55**

mechanism, in this case a ring binder mechanism 13 of customary kind, fastened to the top of plate 10, as by riveting. The plates are here connected with each other by hinge parts 8 and 12 and normally held together by latch 9' and notch 9.

It will be seen that the finished binder appears in all respects as a customary simple form of ring binder. It is simply used as such device is in the customary way. But whenever it is desired to put additional sheets, which have not been previously perforated, on the rings, the binder is used as a punch press for perforating purposes.

The user can grasp a ring and pull the spring latch 9' of the plate 10 out of engagement with notch 9 and turn back the whole metal loose leaf mechanism as a unit with the plate 10 to expose plate 5, as indicated in Fig. 5. The sheet of paper is positioned against square edge 7 and plate 10 turned back to operate the punch press. The little cut disks are dropped into recesses 6' from which accumulations can be shaken out at the side edges. In the punching operation the movable platen plate 10 is operated by the loose leaf mechanism 13 attached to its top face as a handle. The rings are convenient handle means for punching operations, while the movement of all the parts with the top plate 10 gives a weight-ed efficient operation. In other words, there is provided a sturdy little platen punch press in which parts of said press function as necessary parts of the binder construction and in this fashion perform double functions. The operation of punching paper and relatching the punch press plates will now be clear.

It is advisable on account of the pivotal movements of the two plates to slightly curve the male

parts 11 of the punch from the hinge line of the plates as a center, so they will enter the female parts with good registration and good punching effect.

When the improved binder is relatched, the user is not ordinarily conscious of the perforating mechanism. It does not add consciously to the weight, it is out of sight, and there are no necessary differences whatever in the outside contour and appearance of the new binder as compared to the binder of the same type which is customarily made without a perforating mechanism.

Various detail changes within the scope of the invention disclosed will of course occur to the builders of loose leaf binders. Therefore, such changes are intended to be included within the scope of the following claim.

I claim:

A sheet perforator structure comprising a platen plate having a square edge flange at one corner to position a sheet, a set of female punching dies extending through said plate, recess means extending upwardly from the bottom of said plate and inwardly from the side thereof and around the outlets of said dies, a second platen plate hinged at the edge of the first plate, said second plate being about the thickness of said corner flange, male punching dies extending from the face of the second plate, said hinged plates being foldable into a flat laminated metal strip formation, a loose leaf binder case having its back panel attached to said first-mentioned platen plate so as to cover said plate while forming open-sided pockets with said recesses on the bottom side of the plate.

CHARLES B. HAMMEN.
